UNITED STATES PATENT OFFICE.

HERMAN ARNOLD, OF GREENWICH, CONNECTICUT.

SHADE-BRACKET.

No. 923,000.

Specification of Letters Patent.

Patented May 25, 1909.

Application filed December 26, 1908. Serial No. 469,207.

To all whom it may concern:

Be it known that I, HERMAN ARNOLD, citizen of the United States, residing at Greenwich, in the county of Fairfield and State of Connecticut, have invented new and useful Improvements in Shade-Brackets, of which the following is a specification.

My invention pertains to shade brackets adapted to be adjusted to fit shade rollers of various lengths; and it consists in the peculiar and advantageous adjustable bracket hereinafter described and claimed.

In the drawings, accompanying and forming part of this specification: Figure 1 is a perspective view showing a shade bracket constructed in accordance with my invention, as properly arranged on a window frame. Fig. 2 is a front elevation of the bracket body. Fig. 3 is a plan view of said body. Fig. 4 is a side elevation of the adjustable member of the bracket. Fig. 5 is a plan view of the same.

Similar letters designate corresponding parts in all of the views of the drawings, referring to which:

A is a portion of a window frame, and B is the body of my novel bracket, which is designed to be fixed on the face of the frame by nails or screws passed through apertures *a* in its rearwardly projecting end portions *b*. The said projecting portions *b* bear against the face of the window frame A, and consequently a space *c* is afforded between said face and the intermediate portion *d* of the body, which intermediate portion is provided with an opening *e* and notches *g* in the lower wall *f* of the opening, for an important purpose hereinafter set forth.

My novel bracket comprises the body B and the adjustable member C. The said adjustable member C, like the body B, is formed of a single piece of metal or other suitable material, and has a forwardly reaching portion *h*, an enlargement or flange *i* at the rear end thereof, a recess *j* in the lower edge of the portion *h*, and a flange *k* extending laterally from one side of the portion *h*, at a point immediately in front of the recess *j*.

In the practical use of my novel bracket, the parts are relatively arranged as shown in Fig. 1—that is to say, with the enlargement or flange *i* of the adjustable member C in the space *c* back of the intermediate portion *d* of the body B, and the portion *h* of said member C extending forwardly through the opening *e* in the body and so that the recessed part *j*

is seated in one of the notches *g* of the body, and the flange *k* rests in front of the body and against the forward or outer side thereof.

When the member C is placed as stated in the body B, the member C will be supported by the body and securely held against movement in the direction of the length of the body, this being due to the seating of the recessed part *j* in one of the notches *g* of the body. It will also be observed that when the member C is placed as stated, the enlargement or flange *i*, close against the rear side of the body wall *f*, and the flange *k* close against the front side of said wall *f*, will preclude lateral swinging or casual movement of said member and render the connection between the same and the body rigid and strong as is desirable.

When it is desired to adjust the member C in and lengthwise of the body B to fit said member C to a particular shade roller, it is simply necessary to raise the member until the upper wall of its recess *j* is above the upper edge of the body wall *f*, and then move the member laterally in the direction of the length of the body to the point desired, and then move the member downwardly to seat it in the adjacent notch *g* of the body, in which position it will be retained by its own weight and the weight of a shade roller when the latter is engaged with it.

While the bracket illustrated is shown as provided in its member C with a circular aperture, it will be obvious that the member may be provided with either a circular aperture or an angular aperture according to the side of a window frame on which the bracket is to be used, or else may be provided with any other suitable means to receive an end appurtenance of a shade roller.

It will be understood from the foregoing that the recess *j* in the member portion *h* renders it unnecessary to make the opening *e* unduly high and in that way contributes to the compactness and strength of the bracket; also, that the front wall of said recess *j* serves by bearing against the front side of the body to assist in preventing sagging of the forward end of the member C.

Having described my invention, what I claim and desire to secure by Letters-Patent, is:

In a shade bracket, the combination with a body having an opening, the lower wall of which is horizontal, and also having vertical notches in said lower wall, at intervals in the

length thereof; of an adjustable member having a flange disposed back of the body and a portion extending forwardly from said flange and through the opening in the body, and also having a recess in the lower edge of the said portion, and a flange extending laterally from the portion and separated from the first named flange by a space corresponding to the thickness of the body, whereby when the portion above the recess is seated

in one of the notches of the body, the body will rest snugly between the two flanges of the adjustable member.

In testimony whereof I have hereunto set my hand in presence of two subscribing witnesses. 15

HERMAN ARNOLD.
